PATTERN MECHANISM FOR LOOMS

Ivar O. Moberg, Lowell, Mass.

Application March 5, 1948, Serial No. 13,306

15 Claims. (Cl. 139—71)

1

This invention relates to looms and more especially to dobbies, head motions, and similar mechanisms used in looms to produce special weaves which cannot be made automatically in plain looms. For convenience these mechanisms will be referred to as "dobbies" or "dobby motions."

When it is desired to weave a pattern which requires more changes in weave than can be produced in a plain loom, the natural expedient is to use a dobby motion. Also, if the pattern to be woven is such that it cannot be produced practically with a dobby, then it becomes necessary to use a Jacquard loom. However, the practical disadvantages of these latter looms are such that they are employed only with considerable reluctance.

The present invention aims to devise a mechanism of the dobby type which can be used to produce a variety of weaves far beyond the range of the present dobbies and which, in addition, will afford a high rate of production and will be thoroughly reliable in operation. In other words, the invention has for its chief object to devise a mechanism which can do everything that the present conventional dobbies can do and much that they are unable to do.

An important use for such mechanism occurs, for example, in the manufacture of electrically heated blankets, such as those disclosed in my Patents Nos. 2,203,918 and 2,432,785. Each of these blankets comprises at least four and, more commonly, five or six different weaves throughout its entire length. Consequently, the total number of picks or filling threads in one of these blankets is at least 3,000 which requires pattern chains of an impractical length. Thus, for a single index dobby a chain of 3,000 bars would be required, while a double index dobby would reduce this number to 1500 bars, and a double cylinder dobby would require a chain of over 700 bars. In practice a chain containing more than 400 bars is generally considered to be impractical. Of course a Jacquard loom also would require a chain of 3,000 cards to produce one of these blankets, but because, in this case, the weave would be controlled by cards instead of bars, as in the dobby, long chains such as those just described are not considered to be impractical. However, the Jacquard loom when employed to manufacture one of these electric blankets has several serious disadvantages, such as

1. It is costly to run and maintain;
2. It is expensive in changing over from one fabric construction to another;
3. The cost of cards and lacing is very high;

2

4. The frequency of "drop stitches" results in producing a high percentage of blankets which are useless for electric wiring because the channels through which the wires are threaded are blocked; and

5. There are relatively few Jacquard looms in existence.

The present invention provides a mechanism of the dobby type with the aid of which these 10 blanket fabrics can be manufactured at a substantial saving in expense as compared to their production in Jacquard looms.

The nature of the invention will be readily understood from the following description when read 15 in connection with the accompanying drawings, and the novel features will be particularly pointed out in the appended claims.

In the drawings,

Fig. 1 is a front elevation of a loom equipped 20 with a mechanism embodying the present invention;

Fig. 2 is an elevation of the right-hand side of the construction shown in Fig. 1;

Fig. 3 is an elevation of some of the parts of 25 the mechanism shown in Fig. 1 as viewed from the left-hand side of the machine;

Fig. 4 is a vertical, longitudinal, sectional view through parts of the mechanism illustrated in Fig. 1;

Fig. 5 is a transverse, vertical, sectional view 30 taken substantially through the shaft of the cylinder mechanism;

Fig. 6 is a front elevation of parts for driving the main shaft of the latter mechanism;

Fig. 7 is a plan view of the lever mechanism 35 at the top of Fig. 1;

Fig. 8 is a side view showing some details of the dobby finger mechanism;

Fig. 9 is a vertical, sectional view showing two 40 arrangements for operating the dobby fingers;

Fig. 10 is a side elevation, partly in section, showing the relation between the pawl and its ratchet wheel; and

Fig. 11 shows a modified form of pin cylinder.

45 The invention is here disclosed as embodied in a dobby of a common commercial form applied to a high-speed Crompton and Knowles Model No. C4 loom. The dobby chain has been eliminated, but all of the other common dobby parts have been retained.

Referring to Fig. 2, it will be observed that the mechanism there illustrated includes the usual dobby jacks 2 supported in an orthodox dobby frame 3 and connected with a set of harnesses, one of which is shown at 4. Also, as illustrated

in Fig. 4, the dobby jacks are connected to the jack backs 5 mounted in the frame in the usual manner, the mechanism including upper and lower sets of dobby hooks 6 and 7 associated with a set of dobby fingers 8, dobby needles 10, and upper and lower dobby knives 11 and 12, respectively. The knives are operated by rocker arms 13—13' mounted on a shaft 14. Fig. 1 shows the drive rod 15 connecting one of the rocker arms with the dobby crank 16 fast on the bottom shaft or cam shaft 17 of the loom which rotates once for each two picks of the loom. All of the mechanism above described is constructed, arranged, and operates in the well known manner.

The dobby cylinder which, in the customary construction carries the dobby chain, is shown at 18, Fig. 1, and it may be left in place. It is mounted on the shaft 20 which is here utilized in a novel manner.

According to the present invention the customary pattern chain is replaced by a series of cylinders each carrying several rows of pins, all of these cylinders being mounted on a rotatable carrier and spaced apart equally around the axis of the carrier. Mechanism is provided whereby the cylinders can be revolved around their own axes, and the entire carrier, with the cylinders, can be rotated around the axis of the carrier so as to bring any desired cylinder into operating position. The machine also includes a set of special dobby fingers arranged to operate the regular fingers. The uppermost pin cylinder at any instant is in position to operate these special fingers selectively, and the cylinders themselves may be revolved by a sun gear driven from the regular dobby cylinder shaft 29.

Referring to Figs. 4 and 5, the pin cylinders just described are there shown at 21, six of these cylinders being mounted for rotation around their individual axes in a carrier comprising heads 22 and 23 mounted to rotate around the shaft 24 which is supported for rotation on an arm 25 and a bracket 26, both secured rigidly to the dobby frame. At the left-hand end, Fig. 5, a sun gear 27, secured on the shaft 24, meshes with planetary gears 28 fast on the ends of the respective pin cylinders 21. Each cylinder carries several rows of pins, in this particular construction eight such rows being provided, and the uppermost row of pins in the cylinder which is on top at any instant is arranged to operate the special or supplemental dobby fingers 30, as will be evident from an inspection of Fig. 4, in the same manner that the pins on the bars of the orthodox dobby chain operate the dobby fingers. Preferably each finger is counterweighted, as indicated at W, and is provided at its lower side with a groove or "run" for the pins cooperating with it, just as are the regular dobby fingers. These special fingers are supported in parallel, side by side relationship, but are held apart by front and rear spacers or combs S and S', and they are all fulcrumed on the stationary shaft 29. Also, each special finger 30 is connected by a link 31 with one or more regular dobby fingers 8, as will be understood from an inspection of Figs. 8 and 9. In the arrangement here used each link 31 carries a cross pin 32, Fig. 9, at its lower end so that it operates two dobby fingers 8. This is typical of the single index type of dobby. In the double index dobby the link is made as shown at 31' at the right of Fig. 9, where it operates a single dobby finger 8.

Thus each row of pins on the uppermost cylinder 21 in the carrier 22—23 operates through

the special fingers 30 and their connections with the regular dobby fingers to produce the same changes in weaving that could be produced in the orthodox dobby motions.

That is, the lifting of any dobby finger 30 results in lowering the right-hand ends of the two regular dobby fingers 8 controlled by it, and this motion lowers the dobby hooks 6 and 7, controlled by those particular fingers, into position for actuation by the dobby knives upon the next oscillating movement of the rocker arms. The jacks connected with these particular dobby hooks consequently are operated to raise their respective harnesses.

By revolving the topmost cylinder 21 a pattern, predetermined by the positions of the pins in the different rows, can be produced and repeated or changed, as desired. It may here be pointed out that the pins used in the cylinders 21 preferably are like those used in the regular pin bars of the common forms of dobby chains.

Rotation of the cylinders 21 for the purpose just described is produced by revolving the sun gear 27 around its own axis while the carrier 22 remains stationary. For this purpose the shaft 24 is equipped at its right-hand end, Fig. 5, with a sprocket wheel 33, Figs. 2 and 5, and this wheel is driven by a chain 34 operated by another sprocket wheel fast on the regular dobby cylinder shaft 20. An idler 35 is adjustable to keep the desired tension on this chain. The shaft 23 is driven through a clutch 36, Figs. 1 and 6, arranged to slip under an overload, a positive clutch 39' and an intermittent double worm gear mechanism 37 driven by the shaft 38 which, in turn, is driven through connections with the crank shaft of the loom in the usual way. This shaft 38 also drives the box chain 40 at the head of the frame. It makes one revolution for each two picks of the loom. The loom partly shown in the drawings, however, is assumed to have four boxes at one end and one box at the other, so that changes of boxes can be made only on alternate picks when the shuttle is at the four box end. In this machine the intermittent double worm drive 37 is designed to produce one-sixth of a rotation of the shaft 24 for every pick of the loom, and this movement is transmitted through the connections above described to the pin cylinder 21 in operative position to give it one-eighth of a rotation around its own axis, there being eight rows of pins in each cylinder. This brings another row of pins into operative position at every pick. Thus each row of pins determines the arrangement of warps that will be produced for the next succeeding pick, and that arrangement can be predetermined by the positions of the pins in the cylinder.

As will be obvious to those skilled in this art, the number of pin cylinders 21 used in the carrier 22—23 can be made greater or less than the number shown, and also that the number of rows of pins in each cylinder can be varied, changes in the timing of the movements of the carrier and the cylinders being produced to make them operate as above described. For example, if each cylinder carries eight rows of pins, then the rotative movement imparted to the carrier through the shaft 20 and chain 34 will be one-eighth of a revolution of the cylinder 21 in operative position, although all the other cylinders will be rotated simultaneously and to the same extent.

When it becomes desirable to rotate the carrier 22—23 to move one cylinder 21 out of top central or operative position and to bring an-

other into that position such a shift is produced under the control of the box chain 40. Normally the carrier is held in its adjusted position by means of a roll 41, Fig. 3, which is arranged to enter any one of a series of curved depressions or sockets *a* formed in the carrier head 23 between adjacent planetary gears 28, this roll being mounted on the end of a section 42 of an arm 43 pivoted at 44, the section 42 being longitudinally adjustable by the screw and slot connection 45. A spring 46 holds the arm yieldingly in position to maintain the roll 41 seated in any socket *a* which may be brought into cooperative relationship to it. It should be observed, however, that the carrier includes a central sleeve 29, Fig. 5, to which the heads 22 and 23 are rigidly secured; this sleeve being mounted to revolve around the shaft 24 and extending at the right beyond the carrier and having a ratchet wheel 54 keyed or pinned to said extension. The ratchet wheel has a number of pin teeth equal to the number of cylinders in the carrier and spaced apart by the same angular distance that the cylinders are spaced around the shaft 24.

For the purpose of rotating this carrier from one position to another, a reversible pawl and ratchet mechanism is provided comprising a pawl 47, best shown in Figs. 2 and 10, having an approximately elliptical head section and an elongated tail piece 47' consisting of a bar, integral with the pawl 47, pivoted to the rocker arm 13' at 48 and slideable through a normally stationary guide 50. Thus the pawl is reciprocated by the rocked arm once in each revolution of the cam shaft 17, which shaft also makes one revolution for each two picks of the loom.

The pawl carries an upper dog 51 and a lower dog 52, both adjustably mounted on the elliptical section of the pawl 47. These dogs are arranged to engage any one of the series of six pins 53, Fig. 5, in said ratchet wheel 54. Consequently, if the pawl 47 is allowed to drop far enough to enable the dog 51 to engage one of the pins 53, it will operate upon the next right-hand stroke, Fig. 2, of the pawl to rotate the cylinder carrier 22-23 clockwise one-sixth of a revolution, thus bringing a different cylinder into position to operate on the special dobby fingers 30. On the other hand, if the pawl 47 is lifted far enough to enable the dog 52 to engage said pins 53, then upon the next right-hand stroke of the pawl it will swing the carrier 22-23 in a counter-clockwise direction, Fig. 2, one-sixth of a revolution, thus bringing a different cylinder into operative position. Normally the pawl 47 is held by its supporting mechanism in an intermediate position where it can not move the carrier in either direction, although it is constantly reciprocated in timed relation to the operation of the loom by its connection with the rocker arm 13'.

As above indicated, this operating mechanism for the carrier is under the control of the box chain 40, and such control is afforded by suspending the guide 50 from one arm of the lever 55 at the head of the frame by means of a link 56, Figs. 1 and 2, and a universal joint 56'. This lever is fulcrumed on a floating lever 57, Fig. 1, which, in turn, is pivoted at 59 on a stationary bar 58, Fig. 7, supported horizontally on frame parts at the head of the machine, and a spring 60, Fig. 1, acts on the lever 57 to pull it down yieldingly. Adjustably connected with the upright arm of the lever 55 by means of a link 61, Fig. 1, is a rocking inverted T-shaped lever 62 fulcrumed at 63 on the bar 57. Two links 64 and

65 pivotally connect the opposite ends of the cross piece of this lever 62 with two parallel, approximately horizontal bars 66 and 67, both fulcrumed on the shaft 69 and both carrying ball runs *b*-*b*, Figs. 2, 3 and 4, which are positioned directly over the margins of the chain 40, which controls the cycle of operations of the loom.

As above stated, this is the box chain of the machine. It is driven from the shaft 38, Fig. 1, 10 through the bevel gear connection 68, shaft 70, and gear connections at the right of the frame with a shaft 71, Figs. 1 and 4, on which a Geneva driver 72 is secured. This member drives the Geneva wheel 73, loose on the shaft 74 but attached to the sprocket wheels which drive the box chain 40, the arrangement being such that this chain is driven one bar for each two picks of the loom.

The extent to which the levers 66 and 67 can drop is limited by two stops, that for the lever 66 being shown in Fig. 2 and comprising a reversely curved stop and guide bar 75 having a slot therein through which the lever passes freely and with its upper end bent over the bar 58. A stop screw 76 is threaded through this horizontal end portion of the bar 75 where it will engage the top of the stationary bar 58 and limit the downward movement of the lever 66. A similar arrangement is provided to cooperate with the lever 67 and the corresponding parts are indicated by the same, but primed, numerals. These stops are used to adjust and to equalize the normal positions of the two levers 66 and 67.

This chain mechanism and the parts for driving it are standard equipment on the particular machine shown; the chain carrying rolls or "balls" for operating the box motion. According to the present invention the pawl 47 is brought into operation to feed the pin cylinder carrier 22-23 in one direction or the other by means of half rolls, such as those shown at 80, which are mounted on the opposite margins of the chain where they cannot interfere with the mechanism for controlling the selection of the shuttles, but they are in position to raise one or the other of the levers 66 or 67 when they are brought under the ball runs carried by said levers.

As will be seen from an inspection of Figs. 1 and 2, if one of these half rolls or balls raises the lever 66, it will tip the rocking lever 62 in a counter-clockwise direction, lifting the center pivot 63 of said lever against the tension of the spring 60, thus operating through the link 61, bell crank lever 55 and rod 56 to raise the pawl 47. This will result in producing a counter-clockwise rotation of the pin cylinder carrier. On the other hand, if one of the half balls raises the lever 67, motion from it will be transmitted through the connections just described to lower the pawl 47 and thus to create, an instant later, a clockwise rotation of said carrier.

It may here be pointed out that the cylinders 21 have been shown equipped with eight rows of pins or pegs, which is a typical arrangement for 65 single indexing. Occasionally the holes provided in the cylinders to receive these pegs will be double rows. This arrangement is best shown in Fig. 11 which illustrates a short section 21 of one of the pin cylinders shown in Fig. 5. The pin holes and pins *P* are arranged as shown in the latter figure, but double rows are made by forming additional holes *P'* which are slightly offset both circumferentially and axially from the holes *P*. For double indexing additional pins will be placed, as required, in these holes *P'* to operate the addi-

tional dobby fingers. That is, there will be twice as many dobby fingers for double indexing as for single indexing. One set of fingers will be operated by the pins P and the other set by the pins P'.

The number of holes in a horizontal row will correspond to the maximum number of harnesses to be operated by the dobby, and that number may be greater or less, as required for individual situations. A typical number of holes in each horizontal row is sixteen, but the number of pegs or pins used may be much less. These holes are, of course, spaced lengthwise of the cylinders by a distance equal to the gauge of the dobby.

The double intermittent worm drive shown in Fig. 6 will turn the standard dobby chain cylinder 60° for each revolution of the loom crank shaft, but in the present mechanism this motion is transmitted through the sprocket and chain drive 33-34 and the planetary gearing up to the pin cylinders so that each cylinder makes one complete revolution for eight picks in a filling repeat. To change this set-up for a double indication, a single intermittent worm will be substituted for the double intermittent worm shown in Fig. 6, as is usual in driving the prior art dobby chains. If the set-up shown were arranged for a double index indication, all sixteen rows of holes would be utilized and each pin cylinder would make a complete revolution in sixteen picks in a filling repeat.

From the foregoing it will now be understood that the invention provides a novel form of dobby motion in which the dobby chain and the objectionable features attending the use of that chain are eliminated. In its place a multicylinder pattern mechanism is provided which is exceedingly reliable, can readily be modified to accommodate the requirements of different weaves or fabric pattern effects, and with which a much wider range of woven patterns can be produced than would be practical with a conventional dobby mechanism. For example, while the mechanism has been invented and developed primarily to meet the requirements of the manufacture of electric blankets, it is equally useful in the production of bed spreads, table cloths, curtains, towels, and any woven textile product in which two or more basic weaves occur at long intervals.

Also, the changing of the pins in the pin cylinders 21 in order to shift from one pattern to another is simplified as compared to the corresponding operations in the orthodox dobby mechanism, particularly if the new pattern to be produced is complicated.

Another unique and valuable feature of this mechanism is the fact that the pin cylinder carrier can be rotated either backward or forward. This feature reduces the number of pattern-controlling elements required in making complicated weaves. As above stated, this mechanism will do everything that the prior art dobbies will do and much that they cannot do. For example, the electric blankets disclosed in my earlier patents above referred to can be manufactured in a standard loom equipped with this mechanism whereas, as above stated, it has been found necessary heretofore to manufacture such blankets in Jacquard looms.

The operation of the machine has been disclosed so fully in connection with the foregoing description of structure that any further statement as to operations is believed to be unnecessary.

The machine shown has been illustrated in connection with the standard make of loom most

commonly used in the manufacture of blankets. But it will be obvious to anyone skilled in this art that the invention is equally applicable to other standard looms and can likewise be incorporated in those special mechanisms for handling warps, such as two-cylinder dobbies, head motions, and any of the commercial mechanisms of the dobby type. The adaptation of this invention to such other looms and dobby mechanisms will be obvious to any mechanic skilled in their construction and use. For example, in applying this mechanism to some looms, it will be found more convenient to use the double acting pawl 47 in a vertical position and to drive it from a cam located on the loom cam shaft.

Also, while the machine as above described and as illustrated with eight rows of holes in each cylinder makes it possible to produce any weave with two, four or eight picks in a filling repeat with a single index, and any weave with two, four, eight or sixteen picks in a filling repeat with a double index, it should be understood that the cylinders may also be made with six or twelve rows of holes for weave repeats on three, six or twelve picks.

Consequently, while I have herein shown and described a typical embodiment of my invention, it will be evident that the invention may be embodied in numerous other forms without departing from the spirit or scope thereof.

Having thus described my invention, what I desire to claim as new is:

1. A dobby mechanism comprising a set of dobby fingers, dobby jacks constructed to be connected with the harnesses of a loom, mechanism arranged to be brought into action by said fingers to operate said jacks selectively, and pattern mechanism comprising a series of cylinders, a series of rows of pins mounted on each cylinder, means supporting said cylinders for movement into and out of operative relation to said fingers to cause the rows of pins on any cylinder in said operative relation to actuate said fingers selectively, and mechanism for revolving any cylinder in operative position to bring another row of pins into operative relationship to said fingers.

2. A dobby mechanism comprising a set of dobby fingers, dobby jacks constructed to be connected with the harnesses of a loom, mechanism arranged to be brought into action by said fingers to operate said jacks selectively, and pattern mechanism comprising a series of cylinders, a series of rows of pins mounted on each cylinder, a carrier on which said cylinders are mounted for rotation around their respective axes, and mechanism for revolving any cylinder positioned in cooperative relationship to said fingers to present the respective rows of pins one at a time to said fingers in operative relationship thereto.

3. A dobby mechanism according to preceding claim 2, in which said cylinders are supported on said carrier in a circular series arranged around a common axis, in combination with mechanism for rotating said carrier around said axis to bring said cylinders one at a time into operative relationship to said fingers.

4. A dobby mechanism according to preceding claim 2, in which said cylinders are supported on said carrier in a circular series arranged around a common axis, in combination with mechanism for rotating said carrier backward and forward, as may be desired, to bring said cylinders one at a time into operative relationship to said fingers,

and mechanism for revolving any cylinder positioned in cooperative relationship to said fingers to prevent the respective rows of pins one at a time to said fingers in operative relationship thereto.

5. A dobby mechanism according to preceding claim 2, in which said cylinders are supported on said carrier in a circular series arranged around a common axis, in combination with mechanism for rotating said carrier around said axis to bring said cylinders one at a time into operative relationship to said fingers, said mechanism for rotating said cylinders comprising a planetary gearing including a sun gear mounted to revolve around said axis and planetary gears meshing with said sun gear and secured, respectively, to said cylinders.

6. A dobby mechanism according to preceding claim 2, in which said cylinders are supported on said carrier in a circular series arranged around a common axis, in combination with mechanism for rotating said carrier around said axis to bring said cylinders in a predetermined order into operative relationship to said fingers, said mechanism for rotating said cylinders comprising a planetary gearing including a sun gear mounted to revolve around said axis and planetary gears meshing with said sun gear and secured, respectively, to said cylinders, said means for revolving the carrier comprising a tubular shaft rigid with said carrier and encircling the driving shaft of said sun gear.

7. A dobby mechanism according to preceding claim 2, in which said cylinders are supported on said carrier in a circular series arranged around a common axis, in combination with mechanism for rotating said carrier around said axis to bring said cylinders one at a time into operative relationship to said fingers, said mechanism for rotating said cylinders comprising a planetary gearing including a sun gear mounted to revolve around said axis and planetary gears meshing with said sun gear and secured, respectively, to said cylinders, and mechanism for holding said carrier stationary in any position of adjustment while said sun gear is being revolved.

8. A dobby mechanism according to preceding claim 2, in which said cylinders are supported on said carrier in a circular series arranged around a common axis, in combination with mechanism for rotating said carrier around said axis to bring said cylinders one at a time into operative relationship to said fingers, said mechanism for rotating said cylinders comprising a planetary gearing including a sun gear mounted to revolve around said axis and planetary gears meshing with said sun gear and secured, respectively, to said cylinders, a drive shaft for said sun gear positioned coaxially within said carrier, a tubular shaft rigid with said carrier and encircling said drive shaft, and driving elements for said respective shafts secured to them.

9. In a loom equipped with a main pattern mechanism controlling its cycle of operations, a set of dobby fingers, dobby jacks connected with the harnesses of the loom to operate them, mechanism arranged to be brought into action by said fingers to operate said jacks selectively, additional pattern mechanism for operating said fingers; the latter pattern mechanism comprising a series of cylinders, a series of rows of pins mounted on each cylinder, means supporting said cylinders for movement into and out of operative relation to said fingers to cause the rows of pins on any cylinder positioned in said operative relation to

actuate said fingers selectively, and mechanism for revolving any cylinder positioned in operative relationship to said fingers to bring any desired row of pins into cooperative relationship to said fingers, the last named mechanism being driven in timed relationship to the operation of said main pattern mechanism.

10. In a loom equipped with a main pattern mechanism controlling its cycle of operations, a dobby mechanism comprising a set of dobby fingers, dobby jacks constructed to be connected with the harnesses of a loom, mechanism arranged to be brought into action by said fingers to operate said jacks selectively, pattern mechanism for operating said fingers, said pattern mechanism comprising a series of cylinders, a series of rows of pins mounted on each cylinder, a carrier on which said cylinders are mounted in a circular series around a common axis, mechanism controlled by said main pattern mechanism of the loom for rotating said carrier to bring said cylinders one at a time into cooperative relationship to said fingers, and mechanism for revolving any cylinder positioned in cooperative relationship to said fingers to present the respective rows of pins one at a time to the fingers in operative relationship thereto.

11. In a loom equipped with a main pattern mechanism controlling its cycle of operations, a dobby mechanism comprising a set of dobby fingers, dobby jacks constructed to be connected with the harnesses of a loom, mechanism arranged to be brought into action by said fingers to operate said jacks selectively, pattern mechanism comprising a series of cylinders, a series of rows of pins mounted on each cylinder, a carrier on which said cylinders are mounted in a circular series around a common axis, said dobby mechanism including a rocker arm for driving one or more of the dobby knives, a pawl and ratchet mechanism connected with said rocker arm and driven thereby for rotating said carrier to bring said cylinders in a predetermined order into cooperative relationship to said fingers, connections between said pawl and ratchet mechanism and said main pattern mechanism whereby the latter controls the operation of said carrier by said pawl and ratchet mechanism, and means for revolving any cylinder positioned in cooperative relationship to said fingers to present the respective rows of pins one at a time to the fingers in operative relationship thereto.

12. In a loom according to preceding claim 10, a construction in which said main pattern mechanism comprises a pattern chain and said carrier revolving mechanism includes a pawl, together with means for constantly reciprocating it, a ratchet wheel arranged to be operated by said pawl and connected with said carrier to impart rotative movements to it, and connections between said pawl and said pattern chain whereby the latter controls the operation of said pawl on said ratchet wheel.

13. In a loom according to preceding claim 10, a construction in which said main pattern mechanism comprises a pattern chain and said carrier revolving mechanism includes a double acting pawl, together with means for constantly reciprocating it, a ratchet wheel arranged to be operated in both forward and backward directions by said pawl, and mechanism for shifting the pawl from a position in which it feeds the ratchet wheel in one direction to another position for feeding said wheel in an opposite direc-

tion, the latter mechanism comprising a lever mounted to rock between two positions, means operated by pattern elements carried by said chain for tipping said lever from either of said positions to the other, and connections for transmitting motion from said lever to said pawl to shift the pawl from one of its operative positions to the other.

14. A dobby mechanism according to preceding claim 2, in which said cylinders are supported on said carrier in a circular series arranged around a common axis, in combination with mechanism for rotating said carrier backward and forward, as may be desired, to bring said cylinders one at a time into operative relationship to said fingers, and mechanism for revolving any cylinder positioned in cooperative relationship to said fingers to present the respective rows of pins one at a time to said fingers in operative relationship thereto, said mechanism for rotating said carrier comprising a reversible pawl and ratchet mechanism.

15. A dobby mechanism according to preceding claim 2, in which said cylinders are supported

on said carrier in a circular series arranged around a common axis, in combination with mechanism for rotating said carrier around said axis to bring said cylinders one at a time into operative relationship to said fingers, said dobby mechanism including a rocker arm for driving one at least of the dobby knives, and said mechanism for rotating the carrier comprising a pawl and ratchet mechanism connected with and driven by said rocker arm.

IVAR O. MOBERG.
